(57) **CLAIM**

I claim the ornamental design for a spat, as shown.

DESCRIPTION

FIG. 1 is a perspective view of a spat showing our new design in use on a shoe;

FIG. 2 is rear perspective view thereof;

FIG. 3 is a left side elevation view of a spat shown removed from the shoe; the laces are shown truncated to fit on the drawing sheet;

FIG. 4 is a right side elevation view thereof;

FIG. 5 is a top view thereof; and,

FIG. 6 is a bottom view thereof.

The broken lines illustrate environmental structure and form no part of the claim.
